UNITED STATES PATENT OFFICE.

LAWRENCE F. BRAINE, OF NEW YORK, N. Y., ASSIGNOR TO THE RAIL JOINT COMPANY, OF NEW YORK, N. Y., A CORPORATION OF NEW YORK.

INSULATED RAIL-JOINT.

1,207,487.

Specification of Letters Patent.

Patented Dec. 5, 1916.

Application filed August 17, 1914. Serial No. 857,171.

To all whom it may concern:

Be it known that I, LAWRENCE F. BRAINE, a citizen of the United States; residing at New York, in the county of New York and State of New York, have invented certain new and useful Improvements in Insulated Rail-Joints, of which the following is a specification.

This invention relates to an improvement in insulated rail joints particularly of the Weber type, and primarily has in view novel means for effectually protecting the insulation from destructive forces, and also facilitating renewal thereof.

Accordingly, the object of the present invention is to provide a novel and useful arrangement of the insulation for rail joints of the Weber type, whereby more satisfactory results may be obtained than with the conventional disposition of insulation as ordinarily employed in this joint. That is to say, in these joints an insulating shoe-plate is usually employed with the upright member thereof disposed between the outside 25 filler and the upright bolting plate of the shoe angle, thereby leaving the inside of the joint open in the sense of exposing the inside edge of the base member of the insulation, as well as the inside edge of the rail flange. This makes the joint more or less free for the entrance of dirt, cinders, water, and other foreign substances between the bottom of the rail and the upper face of the base member of the insulating shoe plate, 30 and these foreign substances, when present, become a destructive agency due to the constant pounding and chafing between the rails and joint plates, resulting in excessive wear and rapid deterioration of the insulation.

A further objection to the conventional arrangement of insulation referred to is that when the insulating shoe-plate is worn out and requires renewal, it is necessary to dismantle the joint with the exception of the wooden filler blocks, and this dismantling necessarily renders the track unsafe for traffic until the new fiber shoe plate and the other joint parts have been reassembled and fastened together. These objections to an insulating shoe plate arranged with its upright member at the outside of the joint, that is, between the outside filler and the bolting plate of the shoe angle, are entirely obviated and overcome by the improvement of the present invention which

not only provides for covering the inside corner of the joint adjacent and about the inner rail flange, so as to effectually exclude destructive foreign substances, but also involves an arrangement of the insulating shoe plate whereby the same can be readily renewed and replaced by a new one with great facility and without dismantling the joint sufficiently to interfere at all with traffic.

With these and other objects in view which will more readily appear as the nature of the invention is better understood, the same consists in the novel construction, combination, and arrangement of parts herein-after more fully described, illustrated, and claimed.

The essential feature of the invention involved in the novel arrangement of an insulating shoe plate is necessarily susceptible of modification and embodiment in different forms of construction without departing from the spirit or scope of the invention, but for purposes of illustration, certain practical forms of the invention are shown in the accompanying drawings, in which—

Figure 1 is a vertical cross sectional view of the joint on the line 1—1 of Fig. 2. Fig. 2 is a side elevation of the inside of a rail joint of the Weber type illustrating the invention embodied in a one-end insulated rail joint. Fig. 3 is a detail elevation of the short insulating shoe plate employed in a one-end insulated joint of the type shown in Fig. 2. Fig. 4 is a similar view of the compensating steel shoe plate forming a part of the said joint shown in Fig. 2.

Like reference characters designate corresponding parts in the several figures of the drawings.

As indicated, the improvement constituting the present invention is of special utility in its application to the Weber type of insulated rail joint, and may be adapted thereto without any material change or structural alteration therein, and yet contributing the added advantages of securing a better and more thorough protection of the insulating shoe plate, and greatly facilitating renewals thereof. Accordingly, for illustrative purposes, there is shown in the drawings a Weber joint of the well known form including, in combination with the rails 1, the usual steel shoe angle 2 having a rail supporting base plate 3 and the upright girder bolting member 4. This form of joint

also includes an outer wooden or equivalent 5 interposed between the outer sides of the rails and the inner face of the girder bolting member 4 of the shoe angle, an inner wooden or equivalent filler 6 interposed 10 between the inner sides of the rails and the inside metal bolting strap 7, combined with the usual joint bolts 8 passing through the assembled parts and provided with suitable 15 bolt insulation, designated generally by the reference letter 9.

The insulating means for a joint of the character described includes the bolt insulation referred to, an insulating end post 10^a 20 between the meeting ends of the rails, and a fiber or equivalent insulating shoe plate 10 corresponding in its angular form to that of the shoe angle 2 and comprising a horizontal base member 11 and an upright member 25 12 arising from one edge of the base member 10 and integrally or rigidly united therewith. The important consideration of the present invention is to arrange the insulating shoe plate 10 in such a manner as 30 to secure the novel and useful results referred to. In this connection it will be observed that the said shoe plate, while nested within the shoe angle 2, is disposed in an opposite position so that the upright member 35 12 of the shoe plate is located at the opposite side of the rails from the upright member of the shoe angle, and hence lies at the inside of the joint. In this position, the horizontal base member 11 of the insulating shoe plate performs its usual insulating 40 functions between the rail base and the upper side of the rail supporting base plate 3 of the shoe angle, while the upright member 12 of the said insulating shoe plate acts 45 in the additional capacity of a cover which entirely covers and incloses the inside edge 50 of the rail flange. In fact what may be termed the entire inside bottom corner of the joint is covered thereby so that means are thus provided for effectually excluding dirt, cinders, water, and other foreign substances between the bottom of the rail and upper face of the base member of the insulating shoe plate, with the result of greatly increasing the life of the shoe plate 55 within the joint.

A convenient and practical means of removably clamping the insulating shoe plate in its operative position within the joint is 60 illustrated in the drawings, and preferably consists in recessing the outer face of the inside filler 6, as at 13, to accommodate therein the upright cover member 12 of the shoe plate, thereby permitting the inside metal bolting strap 7 to be firmly clamped not only against the said inside filler member 6, but also against the said upright cover member of the shoe plate. In addition to the clamping engagement of the inside bolting strap 7 against the shoe plate, proper

maintenance of the latter within the joint is safeguarded by preferably forming the upright cover member 12 of the shoe plate with keeper notches 14 in the top edge thereof. These keeper notches permit the upper 70 edge of the insulating cover member 12 to project above the bottom line of the joint bolts, which therefore are disposed within the keeper notches and combine therewith to provide means for preventing undue longitudinal movement or displacement of the shoe angle while the joint is subjected to traffic conditions.

By reason of the novel arrangement described for the insulating shoe plate 12, it 80 will be observed that the same not only provides the effectual inside cover above explained, but with this construction and arrangement, when the said shoe plate requires renewal, it is merely necessary to remove the nuts, 18 the washers, 19 and the inside metal bolting strap 7, whereupon by slightly raising the rails, the old insulating shoe plate can be readily drawn out of the joint and a new one slipped in place, without the joint having been dismantled sufficiently to interfere with the traffic.

The invention may be applied to a one-end insulated type of joint by using the insulating shoe plate unit under the leaving rail and combining therewith a compensating steel shoe plate 15 arranged under the receiving rail. This compensating shoe plate 15 corresponds in form to the insulating shoe plate, that is to say, it is of angle formation 95 having a horizontal rail supporting base member 16 interposed between the rail base and the upper side of the shoe angle base 3, and an upright member 17 clamped between the inner filler 6 and the inside bolting strap 100 7. Likewise, the upper edge of the compensating shoe plate 15 has formed therein the keeper notches 14^a receiving the joint bolts and combining therewith to provide the same interlocking function as provided for by the 110 bolts and the keeper notches 14 of the insulating shoe plate. In this form of the invention, however, the intermediate keeper notch in the upright member of the insulating and metal shoe plates, is of an elongated 115 form, as shown, to compensate for variations in the position of the bolt engaging therein, as will occur under some conditions.

In the application of the invention to the one-end insulated type of joint as shown in 120 Figs. 2, 3 and 4 of the drawings, it is preferable to observe the insulating detail of having the insulating shoe plate 10 of a slightly greater length than one-half the length of the joint, so that the inner end of the said 125 shoe plate forms what may be termed an apron extension 20 which overlaps and projects slightly beyond the joint between the meeting ends of the rails, thereby preventing any possibility of short circuits or cur- 130

rent leakage being established between the inner end of the steel shoe plate 15 and the leaving rail of the joint. Furthermore, another feature of practical importance in the 5 maintenance of a joint of this character is that of having the steel shoe plate 15 entirely free to be separately handled instead of being riveted or otherwise secured to the base plate 3 of the shoe angle, as is quite 10 commonly done. Consequently, by reason of making the compensating steel shoe plate 15 a free element, either end of the joint can be provided with the steel shoe plate or with the insulating shoe plate, thus 15 avoiding the use of right hand and left hand parts.

It will be understood that various changes in form, proportion, and minor details of construction may be resorted to without altering the invention or departing from its 20 principles.

I claim:

1. An insulated rail joint including the rails, a shoe angle, an insulating shoe plate

arranged under the one rail and having an 25 upright member disposed at the side of the joint opposite the upright member of the shoe angle, said insulating shoe plate having an apron extension overlapping the joint at the meeting ends of the rails, and a metal 30 shoe plate having a position within the shoe angle beneath the other rail corresponding to the position of the insulating shoe plate.

2. An insulated rail joint including the rails, a shoe angle, and separate insulating 35 and metal shoe plates of corresponding form removably arranged respectively under the separate rails of the joint, and each having its upright member disposed at the inside of the joint and forming a protecting cover for 40 the inside bottom corner of the joint.

In testimony whereof I hereunto affix my signature in the presence of two witnesses.

LAWRENCE F. BRAINE.
